(57) **CLAIM**

I claim the ornamental design for a watch bezel, as shown
and described.

DESCRIPTION

FIG. 1 is a front plan view of a design for the watch bezel;
FIG. 2 is a back plan view thereof, the broken line disclosure
illustrating aspects forming no part of the claimed design;
FIG. 3 is top side view thereof;
FIG. 4 is right side view thereof;
FIG. 5 is bottom side view thereof;
FIG. 6 is left side view thereof; and,
FIG. 7 is a perspective view showing approximately $\frac{2}{3}$ of the
front, the top side, approximately $\frac{3}{4}$ of the right and left sides
respectively and a small portion of the bottom side thereof.
